UNITED STATES PATENT OFFICE.

WILLIAM F. SHICK, ROBERT J. LEHMAN, AND ISAAC J. WALKER, OF DUQUESNE, PENNSYLVANIA.

VALVE FOR HEATING-FURNACES.

SPECIFICATION forming part of Letters Patent No. 705,618, dated July 29, 1902.

Application filed April 28, 1902. Serial No. 104,905. (No model.)

To all whom it may concern:

Be it known that we, WILLIAM F. SHICK, ROBERT J. LEHMAN, and ISAAC J. WALKER, citizens of the United States of America, residing at Duquesne, in the county of Allegheny and State of Pennsylvania, have invented certain new and useful Improvements in Valves for Heating-Furnaces, of which the following is a specification, reference being

had therein to the accompanying drawings.

This invention relates to certain new and useful improvements in valves for soaking-pit furnaces such as are employed for imparting an even temperature to billets previous to passing the same to the rolls to be worked into shape.

In the manufacture of billets it is the practice to employ what is termed a "soaking-pit" furnace, in which the billets are placed and wherein the mass of metal contained in the billet is rendered to substantially the same temperature throughout in order that the same may be properly rolled. These furnaces have flues leading to the exterior of the building in which the furnaces are located, one of which flues is always open for the admission of air and the other of which flues is closed or covered by a valve. These valves as heretofore constructed last but a short time, owing to the intense heat to which the same are subjected burning them out. It is the object of this invention to overcome this difficulty by constructing a valve kept comparatively cool or at least in such a state as to prevent the same warping and thus becoming useless.

Our invention further aims to provide means whereby the valve may be shifted from one position to another, as may be desired and as will be hereinafter further explained.

Briefly described, the invention consists of a valve embodying an inner and an outer casing, with a space therebetween to receive water for maintaining the valve in a comparatively cool state. The outer casing is provided with an opening in its top, and means is connected to the valve for shifting the same to different positions, so as to cover the flues desired, and this construction, together with the other details entering into the invention, will be hereinafter more specifically described

and then particularly pointed out in the claim.

In describing the invention in detail reference will be had to the accompanying drawings, forming a part of this specification, and wherein like numerals of reference will be employed to designate like parts throughout the several views of the drawings, in which—

Figure 1 is a central longitudinal sectional view of our improved valve. Fig. 2 is a transverse vertical sectional view thereof. Fig. 3 is a longitudinal sectional view showing the device in position.

In connection with soaking-pits it is customary to provide two gas-inlets leading to opposite sides of the soaking-pit furnace and through which the gas is admitted alternately, so that both sides of the furnace may be fired to the same degree of heat. These two gas inlets or flues are alternately in communication with the stationary flue leading to the stack, which is generally located outside the building.

We have shown in Fig. 3 how our improved valve is placed in position over the flues, though have not shown the soaking-pit furnace, as our invention resides entirely in the construction of this valve and in the mode of keeping the same in a comparatively cool state. In Fig. 3 we show the gas-flues *a* and *b* and a flue *c*, which is in communication with the stack or chimney. (Not shown.) Our improved valve is so placed in position as to establish communication either between the flues *a* and *c* or the flues *c* and *b*, and it consists of two casings *d* and *e*, the latter within the former, with a space *f* therebetween adapted to receive and retain water for keeping the valve from becoming unduly heated. These casings are secured together by the cross-bar *g*, which serves to seal the space at the lower end, and they are braced by the cross-bars *h* and *k*, the latter extending across the space within the inner casing at the lower edge thereof centrally of its length. The casing *d* is provided at its top with a suitable opening *l*, and also carries on its outer casing at each side of the opening shafts or axles *m*, which protrude beyond the valve at one side thereof to receive the forked

upper ends of the levers *n*, pivoted at their lower ends at any suitable point, and one of which is provided with a crank *o*, so that the valve may be operated to shift from its position, as shown in Fig. 3, into a position to establish communication between the flues *c* and *b*. These valves are generally surrounded by an outer casing *p*, which is provided with a valve *q* of any approved form of construction, the purpose of which is to regulate the quantity of air admitted within the casing *p*. In order to supply water to our improved valve, we provide supply-lines *r* and *r'* through the outer casing *p*.

15 When the valve is in position to establish communication between the flues *a* and *c*, the supply through the pipe *r'* may be cut off by a cock or other suitable means, and when the valve is in position to establish communication between flues *c* and *b* the supply through the pipe *r* may be cut off in a similar manner. It is preferable to provide a double flange *t* around the openings of the flues *a*, *b*, and *c*, within which double flange the valve 25 is seated, so that the water lying within the space inclosed by the casing *p* will not flow into the flues, but will be drained off through the suitable opening *u*. Heretofore in the use of valves for this purpose they have generally been constructed of a single sheet of metal, which soon becomes warped, owing to the intense heat to which it is subjected, requiring the replacing of a new valve. By 30 constructing the valve so as to be filled with

water at all times this danger is entirely ob- 35 viated and the length of life of the valve is materially increased. When the gas is shut off from flue *a* and turned on flue *b*, so as to burn in the opposite side of the furnace, the valve is shifted from the position shown 40 in Fig. 3, so as to rest over the flues *c* and *b*.

In the practice of our invention it will be noted that various changes may be made in the details of construction without departing from the general spirit of our invention, the 45 main principle being the provision of the water-cooled valve in connection with soaking-pit furnaces.

Having fully described our invention, what we claim as new, and desire to secure by Letters Patent, is—

A valve for soaking-pit furnaces, comprising two semicircular casings with a water-space therebetween, the outer casing having an opening in its top, cross-bars at the top 55 and bottom of said casing for spacing the same apart, and means connected to the outer casing for shifting the valve longitudinally, substantially as described.

In testimony whereof we affix our signatures in the presence of two witnesses.

WILLIAM F. SHICK.
ROBERT J. LEHMAN.
ISAAC J. WALKER.
